UNITED STATES PATENT OFFICE.

WALDEMAR SÖRGEL, OF WALTERSHAUSEN, GERMANY, ASSIGNOR TO KÄMMER & REINHARDT A.-G., OF WALTERSHAUSEN, THURINGEN, GERMANY.

DOLL'S EYES WITH LOCKING MECHANISM.

Application filed February 12, 1926, Serial No. 87,903, and in Germany March 19, 1925.

Dolls' heads with sleeping eyes are known in which the parts for locking and releasing the eyes or lids are actuated by turning the doll from one side to the other. The locking means described in U. S. A. Patent 1,412,670 dated April 11, 1922 discloses locking means by which the eyes may be kept open if the doll is in a lying position, but these locking means must have a certain play in their 10 guide so that they can slide very easily, in order that the actuation of the pin is carried out in a simple secure and gentle way. This has however the result that the locking pin may be accidentally released if the child 15 plays with the doll, e. g. that the eyes are not completely opened if the doll is in the upright position as the pendulum is prevented by the released locking pin from executing a full oscillation.

According to the invention this inconvenience is avoided by arranging on the locking pin a guide arm which, if the locking device is in the operative position, projects in the path of oscillation of the pendulum, so that the locking device is automatically 25 returned into the inoperative position by the pendulum striking against said guide arm if the doll is brought into the upright position.

The invention may be applied to sleeping dolls with movable lids or to sleeping dolls with movable eyes. The guide arm instead of being mounted on the locking pin might be fixed on the pendulum.

Whilst the device for locking the movement of the eyes according to the U. S. A. Patent 1,412,670 is applicable only to dolls' heads which are open at the top the present invention presents the advantage that the eye-pendulum and the locking device can be mounted in dolls' heads which are closed on the top and open only at the lower end of the neck.

An embodiment of the invention is shown, 45 by way of example, in the accompanying drawings in which:—

Fig. 1 is a vertical section through a doll's head constructed according to the invention.

Fig. 2 is a front elevation of Fig. 1.

Fig. 3 is an elevation of Fig. 2 seen from below.

The eye balls *c*, *c'* oscillatably mounted in the doll's head in ball sockets *a'* and connected with one another by a transverse *b*

are moved by means of a pendulum *d*, in a manner known per se, if the doll is laid down or lifted, so that if the doll is in the upright position the eyes are opened but closed if the doll is approximately in horizontal position. On the inner surface of the head at the left side a sleeve *e* is fixed past which the pendulum *d* can freely pass. A pin *h* guided by means of a cross pin *g* in the slot *f* of sleeve *e* serves, in the well known manner, as a locking device for the pendulum, the sliding movement of said pin, produced by gravity when the position of the doll is altered, being limited by the cross pin *g* coming in contact with the ends of slot *f*. If the pin *h* is in the extreme outer position (indicated in dash lines in Figs. 2 and 3) it projects in the path of the pendulum *d*. The arrangement according to this invention differs from the arrangement of known type in that on the free end of pin *h* and arm *i* is fixed which serves as guiding path for the pendulum and, with this object in view, is bent from out of the plane of oscillation of the pendulum towards the rear end of sleeve *e*.

If it is desired that the eyes of the doll be open while the doll is lying down, the doll has to be brought into the upright position, so that the eyes are kept open by the pendulum. By inclining the doll to one side the pin *h* is made to project from the sleeve *e* and to get behind the pendulum *d*, the oscillating movements of which are thus locked so that as long as the locking lasts the doll keeps the eyes open. The locking mechanism is released by inclining the doll in opposite direction, so that the pendulum can freely oscillate.

Accidental locking of the pendulum *d* in a sleeping position is prevented by the arm *i* against which the pendulum strikes in its forward oscillating movement so that the pin *h* is pushed back into the sleeve *e*.

I claim:—

1. In a doll's head with sleeping eyes, in combination with the eyes, a pendulum for operating the eyes, a device in the head for locking and releasing said pendulum comprising a sleeve fixed in the head at right angles to said pendulum and at the rear and one side thereof and having a longitudinal slot, a pin slidably mounted in said sleeve for movement into the path of said pendulum, a cross pin mounted in said slidably pin

and engaging with the slot in said sleeve, and a guiding means on said pin for preventing accidental locking of said pendulum.

2. In a doll's head with sleeping eyes, in combination with the eyes, a pendulum for operating the eyes, a device in the head for locking and releasing said pendulum comprising a sleeve fixed in the head at right angles to said pendulum and at the rear and one side thereof and having a longitudinal slot, a pin slidably mounted in said sleeve

for movement into the path of said pendulum, a cross pin mounted in said slideable pin and engaging with the slot in said sleeve, and an arm fixed at one end to the front end of said slideable pin and curved inwards to form an abutment for the oscillating pendulum when said slideable pin is in the locking position to prevent accidental locking of said pendulum.

15
20 In testimony whereof I affix my signature.

WALDEMAR SÖRGEL.
